ARRANGEMENT FOR CLOSING BOXES,
PARTICULARLY IN LARGE GARAGES
FOR MOTOR VEHICLES

Jean Keller, Basel, Switzerland

Application March 20, 1935, Serial No. 12,033
In Switzerland April 25, 1934

2 Claims. (Cl. 20—16)

In garages for motor vehicles, the narrow corridors running along the boxes, offer considerable difficulties to the drivers when driving into and out of the separate compartments, usually called "boxes". Greater width of the roadway (corridor), however, naturally requires a correspondingly greater floor surface, therefore greater capital expenditure. Obviously much is done and a greater facilitation is offered, the drivers, if, only during driving in and driving out, the breadth of the corridor at the entrance of the individual boxes can be enlarged. The arrangement for closing boxes, which forms the subject matter of the present invention, is intended to serve this purpose.

According to the invention the closure for each box forms a projection of the room enclosed between its walls. This projection is formed by two pairs of upright rigid wings, which in closed position represent a prism erected over a trapeze like structure as base. Two main wings forming the one pair of wings, representing the non-parallel trapeze sides, are each rotatably mounted on posts fixed each at the end of a side wall of the box, whilst each of the two wings of the other pair is so linked to one of the main wings, that it can be swung around as desired, but in the closed position takes the direction of the corridor, these two wings together representing then one of the parallel trapeze sides. The saving of floor space achieved by this arrangement can be very considerable in a large garage, where there are several hundred boxes.

The accompanying drawing shows an example of carrying out the subject of the invention.

Fig. 1 shows a front view, in the middle the closure of a box in the closed position and on both sides of the latter one half of the closure of two neighboring boxes.

Fig. 2 is the corresponding plan view, wherein, however, the wings of the closure of the middle box are shown in the open position.

To fixed posts *s* at the front end of the side walls dividing one box from the neighboring box, the main wings *a* of a closing arrangement formed in the manner of a wing-gate, are swingably held. These main wings, which represent the non-parallel sides of a prism erected over a trapeze like structure as base, project in the closed position by an amount *i* into the corridor *k*, as shown in Fig. 2, whilst in the open position, they can be laid against the main wings of the neighboring boxes, after they have been correspondingly swung. To each main wing *a* a secondary wing *b*, preferably of smaller width, is

linked, which secondary wings, when standing side by side in the closed position, take up the direction of the corridor *k*, that is, represent one of the parallel sides of the trapeze like structure. These secondary wings *b* can be swung round at will, that is, up to 360°, thus, either as shown at the left in Fig. 2, swung inwardly and laid against the inside of the already opened main wing *a*, or, as shown at the right in Fig. 2, swung outwardly and laid from the outside each on the secondary wing of the closure of the neighboring box.

After opening the closure of a box the corresponding part of the corridor is free for the entrance or exit of a vehicle, which offers a considerable advantage to the driver. The main advantage resulting from the present arrangement is that on the construction of a garage the corridors can be made narrower, as if the depth of the boxes occupied also the place taken by the closing arrangement enclosing the front or rear part of vehicles put in. Because of their unlimited capability of swinging, neither the secondary wings *b*, nor the main wings *a*, in the open position, hinder, in any way, traffic into or out of a box.

The closures of evacuated boxes in a mammoth garage can be left open, the main wings *a* being turned inwardly so that they rest over the longer of the two parallel sides of the trapeze. Advantageously the two secondary wings *b* are also turned inwardly, so that they rest against the inner surface of the already inwardly turned main wings. This measure obviously facilitates running through the corridor and the accessibility of the boxes adjacent to said evacuated boxes.

All four wings in the example illustrated are filled with wide meshed wire netting, but could, of course, be stiffened by means of struts. One of the secondary wings *b* can, for example, be provided above and below with stops *c*, the other with a lock *e* and a slip-bolt *d* adapted to engage in the floor.

If, for example, the width of the main wings *a* is 100 cms. and these wings, as in the example illustrated, are turned through about 150° against the side walls of a box terminating at the post *s*, the distance *i*, which amount can be saved in the width of the corridor *k* only on one side, is about 90 cms. It is, however, possible to allow the closing arrangement of the boxes to project more than 90 cms. into the corridor, if, for example, the wings *a* are given a breadth of 120 cms. and the angle, which they enclose with the side walls of the boxes, measures more than 150°, the depth of

the boxes between the side dividing walls being correspondingly shortened. Furthermore, the breadth of the boxes, which can suitably be 270-280 cms. is also determinative for the breadth of the wings. In each case the side wings *b* can be narrower than the main wings *a*.

I claim:—

1. A door comprising two rigid uprights, a main wing hingedly mounted to each upright and adapted to swing approximately 180° thereon, a secondary wing swingingly connected to each main wing, the arrangement being such that in the closed position the said main wings and secondary wings take up a position corresponding to the non-parallel and one parallel side of a trapeze, and in the open position said main wings are swung outwardly and the secondary wings folded about said main wings.

2. Arrangement for closing boxes, particularly in large garages for motor vehicles, comprising a fixed post at the front end of each wall dividing the individual boxes, two main wings rotatably mounted on each of said posts, a secondary wing swingingly mounted on each main wing and adapted to swing approximately 180° thereon, the arrangement being such that in the closed position the wings project into the corridor between rows of boxes in the form of a trapeze, the main wings representing the non-parallel sides of the trapeze and the secondary wings taking up the direction of the corridor and together representing one of the parallel sides of the trapeze, whilst in the open position the wings can be swung round to facilitate entry into, and exit from, each box.

JEAN KELLER.
